AUTOMOBILE MIRROR

Leonard Frank Lukey, 236 Chesterville Road,
Moorabbin, Victoria 3189, Australia

Filed Mar. 3, 1975, Ser. No. 554,772

Term of patent 14 years

Int. Cl. D12—16

U.S. Cl. D12—187

FIG. 1

FIG. 2

FIG. 3

FIG. 4

FIG. 5

FIG. 6

FIG. 7

FIG. 8

FIG. 1 is a right rear perspective view of an automobile mirror showing my new design which is mountable on the right side of an automobile;

FIG. 2 is a left front perspective view thereof;
FIG. 3 is a left end elevational view thereof;
FIG. 4 is a top plan view thereof;

FIG. 5 is a left rear perspective view of an automobile mirror showing a second embodiment of my new design the sole difference being that it is mountable on the left side of an automobile;

FIG. 6 is a right rear perspective view of FIG. 5;
FIG. 7 is a right end elevational of FIG. 5; and
FIG. 8 is a top plan view of FIG. 5.

I claim:

The ornamental design for an automobile mirror, substantially as shown and described.
